METHOD OF AND APPARATUS FOR VAPORIZATION OF LIQUID FUEL

Application filed March 21, 1928. Serial No. 263,432.

This invention relates to a method of and apparatus for vaporization of liquid fuel, and has to do particularly with the initial pre-heating and vaporization of liquid fuels for accelerating starting of liquid fuel burners, and also the efficient continuous vaporization after starting.

Heretofore in the design of liquid fuel burners, such as stoves, fire pots and torches, utilizing liquid fuel, it has been customary to utilize a generating tube to which heat has been applied to assist in the vaporization of the liquid fuel. Such generator tubes have varied greatly in design, but they have all presented difficult problems in starting vaporization and in maintaining continued vaporization of the fuel for any length of time. The main difficulty with generator tubes of the prior art in connection with the starting thereof has been the length of time required to efficiently heat the generator tube in preparation for continued vaporization, and the main difficulty in the maintaining of continued efficient vaporization has been the carbonization and choking up of the generator tube. Different theories have been advanced as to the reason for this carbonization and choking up of the generating tube, but regardless of the theory, it is common knowledge that the generating tubes of the prior art do quickly carbonize and choke up, thus requiring frequent cleaning, repairing and replacement.

The present invention contemplates the provision of an entirely novel method and apparatus for effecting the initial preheating of liquid fuel to accelerate the starting thereof, and then controlling the generation of the liquid fuel during normal operation in such a manner as to effect efficient vaporization, and at the same time materially prevent the formation of any carbon. More specifically, this invention relates to the provision of a novel method of starting vaporization of liquid fuel by isolating a predetermined amount of the liquid fuel, arranging said isolated fuel in a helical column, a portion of which is of relatively large cross section, whereby the liquid fuel is quickly vaporized, and whereby the tube for carrying the fuel is

so heated when all such isolated fuel is vaporized as to be in a condition for normal continuous operation. This invention also relates to a novel method of continuously feeding liquid fuel in a relatively small column which is maintained relatively cool and then increasing the size of the column and localizing the heated fuel to said increased column whereby the fuel as it is heated also gradually expands and thus prevents back pressure. This novel method is carried out by means of a generating tube, in combination with a liquid fuel burner, including preheating or starting apparatus, said generating tube having a portion of relatively small diameter (which may be termed of normal standard diameter) and a portion at the end thereof of enlarged diameter. This generator tube is also designed so as to feed the liquid fuel therethrough in a helical column, the cross section of said helical column in said portion of the tube of small diameter being relatively small, and the cross section of the helical column in the portion of the tube of relatively large diameter being correspondingly large, said generator tube and the burner and starting apparatus being so arranged that the blast for starting and the heat for maintaining vaporization is applied to only the large part of the tube, and the helical column being so designed and the tube being of such size that when the supply of liquid fuel is shut off, the remaining fuel in the generator tube will be vaporized and expelled from the generator tube.

In the drawings:

Fig. 1 is a vertical sectional view taken through a stove structure embodying our novel generating tube, and illustrating one manner of starting vaporization in the generator tube preparatory to normal operation.

Fig. 2 is a section taken on line 2-2 of Fig. 1.

Fig. 3 is a section taken on line 3-3 of Fig. 1.

Fig. 4 is a vertical sectional view similar to Fig. 1 but illustrating the generating tube as moved to its normal operating position wherein in the enlarged part thereof is continuously heated to maintain vaporization.

The subject matter of this application is disclosed in application Serial No. 131,868 filed August 27, 1926, the present joint inventors being co-inventors in said application No. 131,868.

In illustrating the present invention it has been shown in connection with a stove structure of the liquid fuel type such as illustrated in application #131,868, but it will be understood that the present method and apparatus may be equally well utilized in connection with any similar burner structure requiring burner elements, and means for vaporizing liquid fuel.

In the particular embodiment illustrated, namely, that of a gasoline stove, a burner structure is shown as at 1, as being stationary, and the generating structure, which includes as a unit the generator tube 2, valve member 3 and tank 4, is mounted for reciprocable movement relative to the burner, as will be obvious by comparing Figs. 1 and 4.

Connecting the generating tube 2 and the burner 1 is a combined preheating and mixing chamber generally designated 5. This combined preheating and mixing chamber is stationary and is provided with a head 6 adapted to receive and guide the end of the generator tube and to supply a suitable supply of air thereto for effecting a combustible mixture. The top part of this member 5 is horizontally pivoted as at 7, and is adapted to be moved to the vertical position shown in Fig. 1, which is the starting position. This top part of the unit 5 is provided with a drip pan 8 formed integrally therewith, and a curved deflecting portion 9 which is adapted to direct the vaporized gases issuing from the end of the generator tube backwardly against the same. This movable portion of the member of housing 5 is adapted to be closed as shown in Fig. 4, whereby the priming cup 8 is moved adjacent the back wall of the member 5, and such member then constitutes a mixing chamber for mixing air with the vaporized gas and conducting the mixture downwardly and backwardly through the passageway 10, to the burner or burners 1.

The generator tube 2 is preferably secured to the valve member 3 and is provided with an enlarged portion 11 and a relatively small but normally sized portion 12. A suitable rod 13 extends the length of this generator tube and is provided at the end thereof with a suitable cleansing wire for keeping the orifice of the jet block 14 clean. A suitable coil of wire 15 surrounds and extends the length of this rod 13, whereby to restrict but at the same time insure positive feeding of the liquid fuel and the gases by capillary action. A second coiled wire 16 is positioned around the coiled wire 15 and extends the length of the enlarged portion 11 of the generating tube. This second coiled wire 16 insures the feeding of the liquid fuel and/or vapor in a

much larger and annular helical column, whereby a considerably greater area of liquid fuel is presented for heating, either for starting or continued operation. As will be later described, the enlarged portion of the generating tube is the only part thereof which is submitted to a vaporizing flame, and it will be obvious that because of this relatively large portion of the generating tube and the presenting of the liquid fuel in a column of relatively large area adjacent the outer wall of this enlarged portion that the liquid fuel and gases will be more quickly and efficiently vaporized.

The enlarged portion 11 of the generator tube is, in the present embodiment, adapted to be positioned either above the preheating or starting flame from the priming cup 8, as shown in Fig. 1, or above the burner 1, as shown in Fig. 4. This preheating tube 2 is made of a predetermined size and capacity, and this is obtained mainly by enlarging the end of the tube to hold a predetermined amount of liquid fuel for starting purposes. This amount of liquid fuel is sufficient, when ignited, to preheat the tube to the required extent to efficiently cause vaporization of any additional fuel fed into the tube. In other words, the generating tube is of such size, and is provided with the capillary coil, so as to hold just the right amount of fuel so arranged and positioned, that when such fuel in the generator tube is vaporized that the apparatus will be in condition for continuous operation.

While the tube 2 is a very good conductor of heat, the rear portion of this tube is so positioned relative to the source of heat, and is of such relatively small diameter, that it is relatively cool compared to the enlarged portion of the tube. It will therefore be obvious that by heating only the enlarged portion of the tube, the liquid fuel will be gradually heated as it is gradually fed forward and will be permitted to expand simultaneously with this gradual heating so that at the hottest part of the tube the gases will have expanded to their greatest extent. The immediate and important advantage of this structure is the prevention of back pressure and the diminishing of heat conducted back to the fuel tank, with the practical result that carbonization is materially reduced.

When the valve member 3 is closed the design of the generator tube 2 and the arrangement of the coiled wires thereof to effect capillary action, together with the presenting of the fuel in a relatively large column, will positively cause all of the liquid fuel to be fed forwardly and quickly vaporized, and will also effect the positive expulsion of all of the fuel or gases from the generating tube at the end of each operation whereby the generator tube is emptied so that there is nothing to carbonize when the same cools down.

The exact structural and mechanical ar-

angement of the various parts of the particular stove structure, as shown, need not be described in detail, as they have no bearing upon the present invention. It will be sufficient to say that the generating unit, which includes the tube 2, the valve housing 3 and the tank 4, is movable to two separate fixed positions, that is, to a collapsed or starting position, as shown in Fig. 1, in which case the 5 enlarged portion 11 of the tube is positioned above the preheater member 9, or fuel pan 8, or to a normal operating position, as shown in Fig. 4 wherein the fuel tank and valve member are positioned in front of the stove 10 and the enlarged portion of the tube is positioned directly above the burner member 1.

In the initial preheating operation the fuel feeding unit and the generating tube, being in the position shown in Fig. 1, the preheater 20 member and fuel pan is moved to the position shown in Fig. 1. The valve in the valve housing 3 is then opened until the generator tube is filled and a small amount of the fuel is directed into the fuel pan 8 whereupon the 25 valve is closed. This fuel in the fuel pan 8 is then ignited and the open flames thereof directed upwardly against the enlarged portion of the generator tube; this generator tube being so enlarged and so formed as to 30 present the fuel in a helical column of relatively large area, the heat from the open flame will quickly cause vaporization of the fuel and an expansion of the same whereby the generated gases will be forced from the 35 jet block and against the curved portion 9 of the preheating member. These emitted gases will be deflected backwardly, rearwardly and upwardly against and around the generator tube, and will also be instantly ignited so as 40 to strike the generator tube in the form of a blast of flame. The enlarged portion of the generator tube will be quickly heated and the liquid fuel in such tube will be gradually fed forwardly to be heated, expanded and emitted 45 from the generator tube. Before or at the time the liquid fuel in the generator tube has been completely vaporized and forced from the tube, the generator tube will be sufficiently heated and will be in condition 50 for normal operation, in which case the pivoted preheater member may be moved into its closed position, as shown in Fig. 4.

When this is done the stove is ready for 55 operation and the fuel feeding unit may be moved towards outward position which corresponds to the position shown in Fig. 4, and the valve member 3 opened to admit liquid fuel to the generator tube. This fuel will be immediately fed under pressure and capillary 60 action to the enlarged part of the generator tube where it will be vaporized, expanded and emitted under pressure from the jet block. These emitted gases passing the air intakes in the head 6 will draw in a sufficient amount of air to produce a combusti- 65

ble mixture, which mixture will be conducted downwardly and backwardly through the passageway 10 and to the burner or burners 1. These gases issuing from the burner 1 may then be ignited to heat the enlarged portion 11 of the generator tube for a continued 70 operation of the stove, as long as desired.

It will thus be seen that we have provided a generating tube, a portion of which is adapted to maintain the raw liquid fuel relatively cool, and another portion of which is adapted to present the fuel in such a form to be heated, and so heating the same as to cause vaporization and permit the expansion of the fuel, the purpose being to materially prevent back pressure and diminish carbonization. We have found that a generator tube constructed in accordance with the disclosure herein, so materially prevents the formation of carbon both during operation 75 and between operations, that liquid fuel burners equipped with such generator tubes, can be operated continuously without cleaning for weeks at a time instead of hours, as 80 has been the usual practice.

It will be understood that while the enlarged portion of the generator tube and the capacity of the helical annular passageway therein preferably bears a predetermined relation to the capacity of the helical annular 90 passageway in the smaller portion, that such proportion may vary widely as well as the relative design thereof, and still permit positive feeding by capillary action and permit expansion of the vaporized fuel as well as 95 effecting emptying of the tube when the burner is shut off.

What we claim is:

1. The method of starting and operating a liquid fuel burner of the type utilizing a 100 generating tube, which consists in initially filling the tube with a predetermined amount of liquid fuel and closing off a further supply, heating said tube to vaporize said predetermined amount of liquid fuel and utilizing 105 the vaporized predetermined amount of fuel to assist in preheating the tube whereby, when substantially all of said fuel has been 110 vaporized, the tube will be sufficiently heated for regular operation and continuous vaporization.

2. The method of vaporizing liquid fuel for liquid fuel burners utilizing generator tubes, which consists in conducting the fuel in a relatively small column towards the heating means, maintaining said relatively small column in a relatively cool condition, and then increasing the size of said column as 115 it enters the heating zone.

3. The method of vaporizing liquid fuel, which consists in conducting the fuel in a relatively small enclosed column maintained at a relatively low temperature, and then increasing the size of the column and subjecting the same to a relatively high heating zone 120 125 130

before combining the same with air to form the combustible mixture.

4. The method of vaporizing liquid fuel, which consists in conducting the fuel in a relatively small column maintained at a relatively low temperature, increasing the size of the column and maintaining the larger column at a relatively high temperature and restricting but positively feeding the fuel by capillary action.

5. The method of conducting fuel through a generating tube forming a part of a liquid fuel burner structure, which consists in maintaining a heating and vaporizing zone, and continuously feeding all the fuel through said zone in a helical column of relatively large diameter.

6. The method of heating and controlling the flow of liquid fuel in burners of the liquid fuel type, which consists in conducting liquid fuel in a helical column of relatively small cross section and convolution, and then conducting said column in a helical path of relatively larger cross section and convolution, initially preheating the column of relatively large cross section to accelerate the vaporization of the liquid fuel, and then constantly applying heat to said column of relatively large cross section only whereby to supply a continuous flow of vaporized fuel or gas for effecting regular operation of the burner.

7. That step in the vaporization of liquid fuel in burners of the type having a generator tube for vaporizing the liquid fuel prior to combining the same with air to form a combustible mixture, which consists in confining the liquid fuel to a relatively small annular and relatively cool column, and then simultaneously enlarging said column and heating the same to cause vaporization.

8. A generating unit for a burner structure of the liquid fuel type having a portion of its length of relatively small cross section and a portion of relatively large cross section, means for conducting the liquid fuel in a closed annular path to said portion of relatively large cross section, preparatory to vaporizing the fuel and mixing the same with air and heating means positioned adjacent said portion of relatively large cross-section only.

9. Burner structure of the liquid fuel type, comprising a starting member, a burner and a generator member connected with a source of liquid fuel supply, said generator member having a portion of relatively small surface area, and a portion of relatively large surface area, said generating member and starting member being arranged for relative movement whereby said starting member will heat the enlarged portion of the generator tube only, for starting the same, said enlarged portion of the generator tube being positioned adjacent said burner, and said smaller portion being positioned relatively

remote therefrom during the normal operation of the burner whereby the liquid fuel initially fed to said generator tube will remain relatively cool until it approaches the relatively large portion adjacent said burner when it will simultaneously expand and vaporize.

10. Liquid fuel burning apparatus comprising a generator tube having a portion of its length of relatively small cross section, and a portion of relatively large cross section, means within said tube for forming an annular helical passageway of small diameter and relatively small cross section in the first portion of said tube and an annular passageway of relatively large diameter and relatively large cross section in the second portion of said tube, and a heating zone for said enlarged portion of said tube, said helical passageway of said enlarged portion being of such predetermined capacity relative to the helical passageway in the smaller portion of the tube as to permit expansion of the heated fuel and prevent material back pressure at the entrance end of the generator tube.

11. A liquid fuel burning apparatus comprising a generating tube having a portion of relatively small diameter and a portion of relatively large diameter, means connected to said portion of relatively small diameter for controlling the feeding of liquid fuel thereto, said portion of larger diameter extending to the end of the generator tube at which point the vaporized fuel is mixed with air, means within said tube arranged to form a helical annular passageway of increasing diameter and cross section, means for applying a vaporizing heat to the enlarged portion only of said generating tube, and means at the entrance of said generating tube for shutting off the fuel supply thereto, said helical passageway being of such size as to have a capillary action on the fuel, and the enlarged portion of said generating tube being of such size that when said supply of fuel is shut off the remainder in the generating tube will be vaporized and expelled to completely empty the same.

In testimony whereof we affix our signatures.

WILLIAM BLASKEWITZ.
